UNITED STATES PATENT OFFICE.

HUBERT AUBURN, OF MOUNT HEALTHY, OHIO.

LOOSE-LEAF BINDER.

Application filed March 1, 1924. Serial No. 696,219.

To all whom it may concern:

Be it known that I, HUBERT AUBURN, a citizen of the United States of America, and a resident of Mount Healthy, in the county 5 of Hamilton and State of Ohio, have invented a new and useful Improvement in a Loose-Leaf Binder, of which the following is a specification.

An object of my invention is to provide a 10 simple and efficient binder that will dispense with locking keys and the like, employed heretofore.

Another object of my invention is to provide a device having a minimum of parts and 15 wherein the parts are so related that same will not readily fail of their intended functions.

These and other objects are obtained by 20 means described herein and disclosed in the accompanying drawings, in which:

Fig. 1 is a perspective view of a loose leaf binder having associated therewith means embodying my invention.

Fig. 2 is a sectional view on line 2—2 of 25 Fig. 1.

Fig. 3 is a perspective view of a locking plate forming a detail of my invention.

Fig. 4 is a view of a locking dog forming 30 a detail of my invention.

Fig. 5 is an enlarged fragmental sectional view showing the parts of a locking device in locked and unlocked positions, all of which form details of my invention.

The device of my invention comprises the 35 conventional base cover 6 fixedly carrying posts 7 and 8. The posts 7 and 8 may be made sectional as is common whereby same may be indefinitely extended in length. A movable cover 9 carries means for adjustably securing said movable cover upon 40 the posts 7 and 8 carried by the base or relatively fixed cover. Said means comprises a tubular housing 10 one end of which may be closed by any suitable plug 11 and the other 45 end of which contains a reciprocating plug or finger piece 12. A reciprocating plate 13 is fixed to the finger piece 12 and is disposed within the chamber 14 formed within the tubular housing 10. The plate 13 has a central perforation 15 through which extends a rivet or stud 16 for limiting the movement 50 of the reciprocating plate 13. At both sides of the aperture 15 there are formed ways 17 and 18 in the reciprocating plate through 55 which the posts 7 and 8 may extend. The ways may be in the nature of apertures as

shown at 17 or may be slots as shown at 18. Adjacent the ways 17 and 18, the reciprocating plate is developed into upwardly extending inclined lugs 19 that cooperate with locking dogs 20 in a manner that will be explained hereafter. The housing 10 is provided with an inwardly extending boss or protuberance 21 that has a yielding action in resisting movement of the finger piece 12, 60

and such protuberance is adapted to lodge in a recess 22 provided in the finger piece 12 whereby to preclude lateral vibration as well as longitudinal displacement of the finger piece 12 when the parts are in the relation 70 shown in Fig. 2. A dog is provided for cooperating with the reciprocating plate 13 at each of the ways 17 and 18. The dogs are of

an L-shape, the shorter leg 26 thereof being provided with lugs 23 and 24 that straddle the reciprocating plate and lodge in apertures 25 provided in the housing 10 thereby limiting the movement of the dog longitudinally of the housing. This is merely a common expedient for precluding shifting of 80

the dogs within the reciprocating plate and other means for effecting this may be employed. The longer leg 27 carries a spring 28 that engages the inner wall of the casing 10 and urges the free end of the longer leg 27 toward the reciprocating plate 13. The said free end of the longer leg 27 is disposed adjacent the inclined lugs 19. Reciprocation of the plate 13 serves to pivotally 85

move the free ends of the dogs, about the engagement of the lugs 23 and 24 upon the walls of the opening 25 against the yielding resistance of the spring 28. Each dog is provided with an aperture 29 that is slightly larger in diameter than the cross section of 90

the posts 7 and 8 and through which apertures such posts extend. The cooperation of parts is such that when a dog is moved to the position shown in dotted lines in Fig. 5 the walls of the aperture 29 are spaced from 95

the posts whereupon the loose cover may be moved upwardly upon the posts and may be removed from the posts. When the dog is moved to the position shown in full line of Fig. 5, the walls of the aperture 29 engage the post at opposite places and thereby effect a binding action upon the post that precludes upward movement of the movable binder or 100 cover 9 yet which will permit the downward movement of the movable binder section upon the post. The housing 10 is provided with suitable apertures 30 and 31 through

which the posts may extend. The lower or fixed binder section may be provided with a casing 32 that is substantially identical in shape to the housing 10 and such casings and housings may be flexibly connected with the cover boards 33 and 34 of the binder.

What I claim is:

In a binder of the class described the combination with a tubular housing having an open end and a sealed end, of a locking device contained within the housing, an actuating plate for the locking device contained

within the housing and having its one end reciprocable through the open end of the housing, and a flanged finger piece carried by the last mentioned end of the actuating plate and adapted to enter the opening in the housing with its flanged portion in abutment with the open end of the housing.

In testimony whereof, I have hereunto subscribed my name this 19th day of February, 1924.

HUBERT AUBURN.
